US0D1094929S

(12) **United States Design Patent** (10) Patent No.: **US D1,094,929 S**
(45) Date of Patent: ** Sep. 23, 2025

(54) **WASH SYSTEM FOR A DISH TREATING APPLIANCE**

(71) Applicant: **WHIRLPOOL CORPORATION**, Benton Harbor, MI (US)

(72) Inventors: **Fabio Cardano**, Galliate (IT); **Umit Can Koralay**, Milan (IT)

(73) Assignee: **Whirlpool Corporation**, Benton Harbor, MI (US)

(**) Term: **15 Years**

(21) Appl. No.: **29/934,506**

(22) Filed: **Mar. 26, 2024**

Related U.S. Application Data

(62) Division of application No. 29/826,346, filed on Feb. 11, 2022, now Pat. No. Des. 1,026,361.

(57) **CLAIM**

The ornamental design for a wash system for a dish treating appliance as shown and described.

DESCRIPTION

FIG. 1 is a top, front perspective view of a wash system for a dish treating appliance shown in the environment of a dish treating appliance;

FIG. 2 is a top, front perspective view of the wash system for a dish treating appliance of FIG. 9, with the dish treating appliance environment removed;

FIG. 3 is a top view thereof;

FIG. 4 is a bottom view thereof;

FIG. 5 is a front view thereof;

FIG. 6 is a rear view thereof;

FIG. 7 is an enlarged right side view thereof; and,

FIG. 8 is an enlarged left side view thereof.

Portions of the wash system for a dish treating appliance and the dish treating appliance environment shown in broken lines form no part of the claimed design.

1 Claim, 8 Drawing Sheets
